(57) **CLAIM**

The ornamental design for a necktie with zipper as shown and described.

DESCRIPTION

FIG. 1 is a top view of a necktie with zipper of an embodiment, where the necktie is untied and the zipper is zipped.

FIG. 2 is a bottom view of the necktie shown in FIG. 1.

FIG. 3 is a top view of the necktie, where the necktie is untied and the zipper is unzipped.

FIG. 4 is a rear view of the necktie shown in FIG. 3.

FIG. 5 is a left-side view of the necktie shown in FIG. 1.

FIG. 6 is a right-side view of the necktie shown in FIG. 1.

FIG. 7 is a front view of the necktie shown in FIG. 1.

FIG. 8 is a rear view of the necktie shown in FIG. 1.

FIG. 9 is a perspective view of the necktie, where the necktie is untied and the zipper is zipped.

FIG. 10 is a perspective view of the necktie, where the necktie is untied and the zipper is unzipped.

FIG. 11 is a perspective view of the necktie, where the necktie is tied in front and the zipper is zipped.

FIG. 12 is a perspective view of the necktie, where the necktie is tied in front and the zipper is unzipped.

FIG. 13 is a perspective view of the necktie, where the necktie is tied in back and the zipper is zipped; and,

FIG. 14 is a perspective view of the necktie, where the necktie is tied in back and the zipper is unzipped.

The evenly-dashed broken lines along the surfaces of the necktie with zipper depict stitching which forms no part of the claimed design. The dash-dot-dash lines depict symbolic break lines which form no part of the claimed design. The various styles of surface shading applied to the surfaces of the necktie with zipper represent a contrast in appearance and form no part of the claimed design. The appearance of any portion of the necktie with zipper between the symbolic break lines forms no part of the claimed design.
